Sheet 1-28 Sheets

F. Vester,

Shoe-Sole Protector,

No. 36,385.

Patented Sep. 2, 1862.

No. 1.

No. 2.

No. 3.

No. 4.

F. Vester,

Shoe-Sole Protector,

No. 36385.

No. 5.

Patented Sep. 2, 1862.

No. 6.

No. 7.

No. 8.

UNITED STATES PATENT OFFICE.

FRANZ VESTER, OF PFORZHEIM, GRAND DUCHY OF BADEN, ASSIGNOR TO CHARLES WAGNER, OF NEW YORK, N. Y.

IMPROVED DEVICE FOR PROTECTING SOLES OF BOOTS AND SHOES.

Specification forming part of Letters Patent No. 36,385, dated September 2, 1862.

To all whom it may concern:

Be it known that I, FRANZ VESTER, of the city of Pforzheim, in the Grand Duchy of Baden, have invented certain new and useful Improvements in Protecting Leather Shoe-Soles from Wear by Means of Metallic Guards; and I do hereby describe and ascertain the same, referring to the accompanying drawing, in which several varieties of my improvement are shown.

I am aware that large nails, studs, and screws have before been employed for this purpose, inserted in the soles of shoes and boots; but all of these devices have had some objectionable features which my device is calculated to remedy.

My device is constructed and applied as follows: I take thin pieces of hardened steel or iron cut to any ornamental form, specimens of which are seen in the Nos. 1 to 8, and insert them in recesses in the face of the leather sole, made exactly to fit them. Through each of these ornamental pieces there is a small hole made and a corresponding hole in the sole, and on the inner side there is put another thin plate or washer inserted flush with the surface of the sole. This may be round, as seen at No. 3 of the drawing. A rivet of softer metal unites the plates with the sole in a permanent manner, and the sole is ready to be applied to the shoe or boot in any of the usual ways.

I do not wish to be understood as claiming metallic studs or other protections to shoes and boots, as that has before been done; but

What I do claim is—

The employment of the thin hardened plates or washers with rivets connecting them with the soles of boots and shoes, substantially in the manner and for the purpose set forth.

FRANZ VESTER. [L. S.]

Witnesses:

J. FERD. WAGNER,
LEOPOLD LEVI.